H. J. MITCHELL,
CUTTER HEAD;
APPLICATION FILED APR. 22, 1921.

1,405,614.

Patented Feb. 7, 1922.

UNITED STATES PATENT OFFICE.

HARRISON J. MITCHELL, OF SEATTLE, WASHINGTON, ASSIGNOR TO P. B. YATES
MACHINE COMPANY, OF BELOIT, WISCONSIN, A CORPORATION OF WISCONSIN.

CUTTER HEAD.

1,405,614.

Specification of Letters Patent.

Patented Feb. 7, 1922.

Application filed April 22, 1921. Serial No. 463,483.

To all whom it may concern:

Be it known that I, HARRISON J. MITCHELL, a citizen of the United States, residing at Seattle, in the county of King and State of Washington, have invented certain new and useful Improvements in Cutter Heads, of which the following is a specification.

My invention relates to simple and improved means for holding or clamping the cutting knives or blades on a cutter-head for woodworking machines.

One object of the invention is to provide an appliance of this general type in which cutter knives of different widths or lengths may be used and firmly held in position by the same adjustable clamping means, hence not requiring the interchange of any parts for knives of different dimensions.

A further or additional feature of the invention resides in simple and efficient means for holding wide or long cutter knives between their edges or ends in such a way that the cutting edge of the knife will be maintained straight even though the knife may have been slightly sprung or distorted as during tempering.

Another purpose of the invention is the provision of a structure of this character which is simple in form, composed of few parts, inexpensive to produce, and effective and reliable in results.

To enable those skilled in this art to have a full and complete understanding of the invention both from structural and functional standpoints, I have illustrated two desirable and preferred embodiments of the same in the accompanying drawing forming a part of this specification and to which reference should be had in connection with the following detailed description.

In this drawing, throughout the several views of which like reference characters refer to the same parts.

Figure 1 is an end view of the improved cutter head;

Figure 2 is a face view of the same;

Figure 3 is a section through one of the knife retaining clamps;

Figure 4 is a face view of a wider knife;

Figure 5 is a fragmentary longitudinal section showing the manner of maintaining such longer or wider knife in place on the cutter head; and

Figure 6 is a fragmentary section showing the holding of the cutter knife between bevelled or undercut roughened or corrugated faces of the securing elements.

Referring to this drawing, it will be perceived that the appliance comprises a somewhat elongated cutter-head or main-body 10, having a central round aperture 11 for the reception of the drive shaft, not shown, such member having a plurality of, in the present instance six, surfaces 12 disposed lengthwise the head with intervening longitudinal grooves or recesses 13 and adapted to be fitted or provided each with one cutter blade or knife 14, these several surfaces being at an angle to and spaced from one another and arranged around the entire head.

Referring to this drawing, it will be perceived that the appliance comprises a somewhat elongated cutter-head or main-body 10, having a central round aperture 11 for the reception of the drive shaft, not shown, such member having a plurality of, in the present instance six, surfaces 12 disposed lengthwise the head with intervening longitudinal grooves or recesses 13 and adapted to be fitted or provided each with one cutter blade or knife 14, these several surfaces being at an angle to and spaced from one another and arranged around the entire head.

Stated somewhat otherwise, the cutter-head is of general, but not exact, hexagonal form, its six faces being slightly separated from one another as indicated.

The number of such faces, and accordingly the number of cutters employed, may be varied as circumstances dictate, being either greater or less than the six specified, the invention in no way being limited in this respect.

Secured flat against one end of this main-body by several fastening screws 15, or by other appropriate means, is a plate 16 having six radiating ears or projections 17 in register with and extending outwardly beyond the corresponding, bit-receiving surfaces 12 referred to, each of such ears having a sloping or undercut face 18 extending inwardly from its outer end to the surface 12.

Each of such projections or lugs constitutes an undercut or beveled abutment wall against which the correlative or complementary, sloping, side edge portion 19 of the cutter blade is adapted to bear, these interfitting parts preventing dislodgment or displacement of the cutter blade.

For the greater portion of its length or for its entire length, each of the six angularly-disposed faces 12 of the cutter-head has a central longitudinal undercut or shouldered groove 20 of general T shape on the opposite sides of which the face is provided with a series of transverse grooves or notches 21 with intermediate teeth forming a ratchet.

Each cutter blade or knife 14 is securely and firmly held in place by a centrally-apertured clamp 28 having a beveled or undercut face 22 adapted to bear on and overlie the correspondingly sloping side edge por-

tion 23 of the cutter, the clamp on its under or inner face along its opposite edge having a rib or heel 24 designed to fit in any one of the spaced notches or channels of the 5 ratchet, as is perhaps most clearly depicted in the upper part of Figure 2.

Each clamp is held in place by a bolt 25 extended through its hole and having its 10 square head 26 received and adjustable lengthwise in the groove 20 and its coating, external, readily-accessible nut 27, the tightening and loosening of which may be easily effected by turning it in the usual manner to fasten and release the associated sharp edged 15 cutter.

In tightening the nut an extremely effective wedge and clamping action on the cutter blade is obtained, all as will be readily understood by those skilled in the art, 20 whereby the proper and effective holding of the cutter knife in position under all conditions of severe service is assured.

Stated otherwise, the tightening or turning of the nut forces the clamp inwardly, 25 and, by means of the coating beveled surfaces, the knife is pushed or forced firmly in under the overhanging abutment wall 17.

Also in screwing up the nut to fasten the clamp, the rib or heel of the latter acts somewhat as a fulcrum about which the clamping member has a slight turning movement, and the cooperating sloping faces of the cutter and clamp make certain that such heel and rib will be in proper engagement 35 with the ratchet tooth on which it bears.

Due to the fact that the clamp and its fastening bolt are capable of adjustment lengthwise the face 12 of the cutter-head, it is adapted to securely hold cutter blades of 40 different widths, the notches of the ratchet being sufficiently near to one another so that one is always available for all transverse dimensions of the cutter knives which the head is adapted and designed to employ.

45 In order to insure the correct and effective cooperation of the ratchet teeth with the rib or heel of the clamp, the inner faces of the ratchet teeth, that is those surfaces facing the plate 16, are preferably, though not necessarily, at right angles to the axis of the head, whereas the outer faces of the teeth are sloping or inclined as shown in Figure 2 to facilitate the inward movement of the clamps thereover and to give the teeth 55 broader bases.

When wider knives or cutters are used, they are ordinarily provided with a central slot or recess 29, as illustrated in Figure 4, to receive an additional holding or clamping 60 bolt 30 having its head in the groove 20 and its nut bearing on the outer face of the knife to maintain the central portion firmly in place.

If in tempering or for any other reason 65 the cutter or knife has been slightly sprung

out of true, such middle bolt will draw the blade down flat onto the cutter head thereby making certain that the comparatively long or wide knife will be maintained straight throughout its entire length.

70 Although I have illustrated and described only two embodiments of the invention, it is to be understood that the latter is susceptible of a variety of incorporations in physical form and that many mechanical changes may be made in the structures depicted and described without departure from the heart and essence of the invention and without the sacrifice of any of its substantial benefits and advantages.

75 For example in Figure 6 I have shown the undercut or bevelled faces of the holding parts 17 and 28 as slightly roughened or serrated to increase their gripping or securing capacity.

80 I claim:

1. In a cutter-head of the character described, the combination of a main body having holding means to engage one side edge portion of the cutter and a series of spaced notches at different distances from said holding means, a clamp adapted to engage the opposite side edge portion of the cutter and designed to fit in any one of said notches depending upon the width of the cutter, and means to maintain said clamp in any one of said notches to hold the cutter in operative position.

85 2. In a cutter-head of the character described, the combination of a main body 90 having an abutment wall to engage one side edge portion of the cutter and a series of spaced notches at different distances from said wall, a clamp adapted to engage the opposite side edge portion of the cutter and designed to fit in any one of said notches depending upon the width of the cutter, and screw threaded means to maintain said clamp in any one of said notches to hold the cutter in operative position.

95 3. In a cutter-head of the character described, the combination of a main body having an undercut abutment wall to engage one side edge portion of the cutter and a series of spaced notches at different distances from 100 said abutment wall, a clamp having an undercut part to engage the opposite side edge portion of the cutter and having a heel to fit in any one of said notches depending upon the width of the cutter, and screw threaded means to maintain said clamp heel in any one of said notches and to cause the clamp 105 to hold the cutter in operative position.

110 4. In a cutter-head of the character described, the combination of a main body having an undercut abutment wall to engage one side edge portion of the cutter and a series of spaced notches at different distances from 115 said abutment wall, a clamp having an undercut part to engage the opposite side edge portion of the cutter and having a heel to fit in any one of said notches depending upon the width of the cutter, and screw threaded means to maintain said clamp heel in any one of said notches and to cause the clamp 120 to hold the cutter in operative position.

125 5. In a cutter-head of the character described, the combination of a main body having an undercut abutment wall to engage one side edge portion of the cutter and a series of spaced notches at different distances from 130 said abutment wall, a clamp having an undercut part to engage the opposite side edge portion of the cutter and having a heel to fit in any one of said notches depending upon the width of the cutter, and screw threaded means to maintain said clamp heel in any one of said notches and to cause the clamp to hold the cutter in operative position.

portion of the cutter and having a heel to fit in any one of said notches depending upon the width of the cutter, and screw threaded means adjustable toward and from said wall 5 with the clamp to maintain the clamp heel in any one of said notches and to cause the clamp to hold the cutter in operative position.

5. In a cutter-head of the character described, the combination of a main body having an abutment wall with an undercut sloping face adapted to engage and overlie a bevelled edge portion of the cutter and having a series of spaced notches at different distances 10 from said wall, a clamp having an undercut bevelled face adapted to engage and overlie an opposite bevelled edge portion of the cutter and having a heel to fit in any one of said notches depending upon the width of the 15 cutter, and a bolt having interlocking engagement with said main body and adjustable with the clamp toward and from said wall and adapted to maintain the clamp heel in the appropriate notch and to cause the 20 clamp to hold the cutter in operative position.

6. A cutter-head of the character described, comprising in combination, a main body having an abutment wall against which 25 a side edge portion of the cutter is adapted to bear, clamping means adjustable toward and from said abutment wall adapted to engage the opposite side edge portion of the cutter, means adjustable toward and from 30 said abutment wall designed to fasten an intermediate portion of the cutter between said edge portions, whereby the same instrumentalities may be employed for holding cutters of different widths on said cutter-head.

40 7. A cutter-head of the character described, comprising in combination, a main body having a series of transverse notches and an undercut longitudinal groove, means

on said body adapted to engage one side edge portion of a cutter, an apertured clamp 45 designed to engage the opposite side edge portion of said cutter and having a heel adapted to enter any of said notches depending upon the width of the cutter, and a bolt fitting in said groove and clamp aperture adapted to 50 tighten the clamp and maintain it in cutter fastening relation.

8. A cutter-head of the character described, comprising in combination, a main body having a series of transverse notches 55 and an undercut longitudinal groove, an undercut abutment wall on said body adapted to engage one side edge portion of a cutter, a beveled apertured clamp designed to engage the opposite side edge portion of said 60 cutter with its beveled surface and having a heel adapted to enter any of said notches depending upon the width of the cutter, and a bolt fitting in said groove and clamp aperture adapted to tighten the clamp and maintain 65 it in cutter fastening relation.

9. A cutter-head of the character described, comprising in combination, a main body having a series of transverse notches 70 and a longitudinal undercut groove, an undercut abutment wall on said body adapted to engage one side edge portion of a cutter apertured between its side edges, a beveled apertured clamp designed to engage the opposite side edge portion of said cutter and 75 having a heel adapted to enter any of said notches depending upon the width of the cutter, a bolt fitting in said groove and clamp aperture and adjustable in the former adapted to tighten the clamp and maintain it in 80 cutter fastening relation, and a second bolt in said groove designed to project through said cutter aperture and hold the intermediate portion of the cutter firmly against said main body.

HARRISON J. MITCHELL.
